UNITED STATES PATENT OFFICE.

AUGUSTE L. SALTMAN, OF EAST ORANGE, NEW JERSEY, ASSIGNEE, BY MESNE ASSIGNMENTS, TO NEW JERSEY PATENT COMPANY, OF WEST ORANGE, NEW JERSEY, A CORPORATION OF NEW JERSEY.

PRIMARY BATTERY.

1,076,789.

Specification of Letters Patent. Patented Oct. 28, 1913.

Application filed February 10, 1911. Serial No. 607,745.

To all whom it may concern:

Be it known that I, AUGUSTE L. SALTMAN, a citizen of the United States, and a resident of East Orange, in the county of Essex and State of New Jersey, have invented certain new and useful Improvements in Primary Batteries, of which the following is a specification.

My invention relates generally to improvements in primary or voltaic batteries, and more particularly to that class in which the negative electrode consists of a plate of oxid of copper, or other depolarizing agent properly molded and agglomerated, and the positive electrode of which consists of a plate or plates of zinc.

My invention includes improvements on the structure described in the patent to Eben G. Dodge, No. 894,487, granted July 28, 1908. In primary batteries of the type described in this patent, both the positive and negative elements are supported by one frame or hanger including an inverted U-shaped member, channel shaped in cross section, which is secured to the battery jar cover by a bolt and nut, whereby the electrodes and their supporting frame or hanger may be easily removed as a unitary structure for any desired purpose such as cleaning or renewals. In batteries of this type the bolt is provided with a wedge shaped head which is drawn into engagement with the walls of the hanger by the nut when the electrodes and their supporting frame or hanger are secured in place to the jar cover. When, however, the nut is removed from the bolt, the latter is no longer held in place in the hanger and is liable to drop out of place, thereby causing inconvenience.

The object of my invention is to provide an efficient connection between the bolt or other suspension means and the supporting frame or hanger or other supporting structure, whereby the bolt or other suspension means is held in place in the supporting frame or hanger or other supporting structure, when the electrodes and their supporting structure are removed from the jar cover; and, furthermore, to provide such a connection that as the nut is tightened up to draw the supporting structure into place beneath the jar cover, the electrical and mechanical contact between the bolt head and

the supporting structure is rendered still more efficient.

My invention consists further in the details of construction and combinations of parts hereinafter more particularly described and claimed.

In the accompanying drawings which form a part of this specification, and in which like reference characters refer to like parts in the several views: Figure 1 is a side elevation partly in section of a portion of a battery embodying my invention; Fig. 2 is an elevation of the structure shown in Fig. 1 at right angles thereto; Fig. 3 is a vertical section taken on the line 3—3 in Fig. 1 and showing certain details of construction; and Fig. 4 is a plan view of the bolt head and a portion of the frame or hanger, and showing a modified form of opening for the bolt in the frame and hanger.

Referring to the drawings, the top or cover of the battery jar is shown at 1.

The numeral 2 indicates a frame or hanger preferably constructed of a strip of sheet copper or copper plated iron or steel, the edges of said strip being turned up to such an extent as to lie flat against the bevel edges of the negative electrode plate 3. The plate 3 is preferably of copper oxid. The cross section of the hanger 2 is channel shaped as is shown in Figs. 1, 3 and 4. The hanger 2 is preferably given the form of an inverted U, the two arms or depending portions of which hold the edges of the negative plate 3. The said plate 3 fits into the channels of the hanger 2 and is held in said hanger by any suitable supporting means, as for example, by lips 4 formed in the lower ends of the depending arms of the hanger 2. The plate 3 is also further clamped in the hanger by a horizontal cross piece or bridging member 5 preferably of similar material and cross-section to the hanger 2, and secured at either end to the sides of the hanger by end projections 6 which extend through openings 8 in the hanger and are bent into clamping position against the outside of the hanger. The sides of the bridging member 5 are provided with depending lips 9 having trapezoidal openings therein registering with a similar opening on the plate 3.

The zinc or positive electrode plates of the

55

75

100

105

battery indicated at 10 are secured to an insulating block or blocks 11 and to the bridging member 5 by a suitable bolt 12. Thus, the zinc plates are supported from the bridging member, and the battery plates and their supporting frame form a unitary structure adapted to be supported from the jar cover by a single bolt or other suspension means.

10 As a means for supporting the frame and the battery plates from the jar cover, I have used a suitable bolt 13 which is preferably screw threaded. The bolt 13 is provided with a wedge shaped head 14, the wedge faces thereof preferably having one or more grooves or keyways 15 formed therein longitudinally of the bolt. The hanger 2 which, as hereinbefore stated, is channel shaped in cross section, is provided with an 15 opening 16 in the base of the channel. The opening may be round, as shown in Fig. 4, or elongated, as shown in Fig. 1, or of other suitable shape. In assembling the parts the bolt 13 is passed through the opening 16 so that the stem of the bolt extends through the opening 16 and the wedge faces are in engagement with the walls of the channel shaped hanger 2. Preferably a slight clearance is left between the shoulder of the 20 bolt head and the base of the channel shaped hanger as is indicated at 17 in Fig. 3, for a purpose hereinafter set forth. The metal of the hanger, particularly of the walls thereof, is then upset over and around the sides, into the grooves, and over and around the base of the bolt head 14, as is clearly shown in Figs. 3 and 4, by any suitable method such as by subjecting the bolt head and the portion of the hanger adjacent 25 thereto, after assembly as described above, to compression between suitably shaped dies. In this manner an efficient mechanical and electrical connection between the bolt and the hanger is secured, and the bolt is held 30 in place by the metal of the hanger upset around it. The bolt then becomes a part of a unitary structure including the battery plates and their supporting frame. This structure may be attached to the battery 35 jar cover 1 by passing the stem of the bolt 13 through a hole 18 in the battery jar cover, and drawing the structure into place by means of a nut 19. On account of the slight clearance between the shoulder of the bolt 40 head and the base of the channel shaped hanger 2, the bolt head may be moved slightly with reference to the walls of the hanger when the nut 19 is tightened on the bolt. The walls of the hanger yield sufficiently, when necessary, to permit this 45 movement, but the grip of the hanger on the bolt head is not loosened; on the contrary, the bolt head is wedged more firmly between the walls of the hanger, thereby 50 producing a more effective mechanical and

electrical connection. It is to be noted that the provision of grooves or keyways in the bolt head longitudinally of the bolt permits the movement referred to without loosening the grip of the hanger on the bolt head. Furthermore, if it is desired to detach the battery plates and their supporting frame from the battery jar cover, the bolt will be retained in place in the hanger and ready for re-attachment to the jar cover.

Having now described my invention, what I claim and desire to protect by Letters Patent is as follows:

1. In a voltaic battery, the combination of a supporting hanger of sheet metal having an opening therethrough, and a supporting bolt therefor, the bolt being extended through the opening and held in place by an upset portion of the hanger, substantially as described.

2. In a voltaic battery, the combination of a U-shaped hanger, channel shaped in cross-section, and a supporting bolt therefor having a wedge shaped head, the wedge faces of the head being in engagement with the walls of the channel and held in place by upset portions of the walls, substantially as described.

3. In a voltaic battery, the combination of a U-shaped hanger, channel shaped in cross-section, and a supporting bolt therefor having a wedge shaped head, the wedge faces being grooved and in engagement with the walls of the channel, the material of the hanger being upset into intimate engagement with the grooved faces and around the edges of the same, whereby the bolt is held in place in the hanger, substantially as described.

4. In a voltaic battery, the combination with positive and negative battery plates, of supporting means therefor, comprising a hanger of sheet metal, and a supporting bolt therefor, the said bolt being secured to said hanger by an upset portion of said hanger, substantially as described.

5. In a voltaic battery, the combination with positive and negative battery plates, of supporting means therefor, comprising a hanger of sheet metal, and a supporting bolt therefor, having a wedge shaped head, said bolt being held in place by a portion of the hanger upset into engagement with and partially surrounding said head, substantially as described.

6. In a voltaic battery, the combination with positive and negative battery plates, of supporting means therefor, comprising a hanger of sheet metal, and a supporting bolt therefor, having a wedge shaped head with the wedge faces grooved, said bolt being held in place by a portion of the hanger upset into intimate contact with the wedge faces and their grooves and around the edges of said faces, substantially as described.

7. In a voltaic battery, the combination with a jar cover, of battery plates and means for supporting the same including a channel-shaped metal hanger having an opening in the channel base thereof, a bolt extended through the opening and having a wedge shaped head, the bolt being held in place by metal of the hanger upset around the bolt head, and having a slight clearance between the base of the channel and the shoulder of the bolt before the plates and supporting means are drawn into place under the jar cover, substantially as described.

8. In a voltaic battery, a unitary structure adapted to be secured to a jar cover by a single suspension, and comprising positive and negative battery plates and supporting means therefor, the said supporting means comprising a hanger, channel shaped in cross-section, and a single suspension bolt having a wedge shaped head, the said bolt being secured to the said hanger by portions of the walls of the hanger upset into engagement with the wedge faces of the bolt head and around the sides and lower edges thereof whereby the bolt is prevented from dropping out of the hanger when the said unitary structure is detached from the jar cover, substantially as described.

9. In a voltaic battery, the combination with a battery jar cover, of a unitary structure adapted to be secured to the jar cover

by a single suspension, the said unitary structure comprising positive and negative battery plates and supporting means therefor, the said supporting means comprising a hanger, channel shaped in cross-section, and a single suspension bolt having a wedge shaped head, the said bolt being secured to the said hanger by portions of the walls of the hanger upset into engagement with the wedge faces of the bolt head, whereby the bolt is prevented from dropping out of the hanger when the unitary structure is detached from the jar cover, and intimate contact between the hanger and the bolt head is insured when the structure is secured to the jar cover, substantially as described.

10. In a voltaic battery, the combination of a supporting hanger, channel shaped in cross-section, and a supporting bolt therefor having a wedge shaped head, the wedge faces being grooved longitudinally of the bolt and the bolt being held in place by material of the hanger upset into the grooves and around the base of the bolt head, substantially as described.

This specification signed and witnessed this 8th day of February 1911

AUGUSTE L. SALTZMAN.
